HATCH COVER ASSEMBLY

Bernard S. Appleton, Woodmere, and Kurt Barth, Seaford, N.Y., assignors, by mesne assignments, to G.M.E. Corporation, a corporation of New York

Application April 26, 1957, Serial No. 655,258

3 Claims. (Cl. 114—202)

This invention relates to the art of hatch covers and 15 more particularly to hatch covers movable in substantially a horizontal plane with respect to a hatchway.

Where marine hatch covers comprise a plurality of extremely heavy rectangular panels which, when in closed position, lie in a horizontal plane over the hatchway, and the cable from a derrick or hoist must be connected successively to each of the individual panels to lift them away from the hatchway and to stack them into position clear of the hatchway so that it is open to receive cargo, the many manual operations required are burdensome and time-consuming, require many personnel and delay the loading and unloading of a ship.

It is accordingly among the objects of the invention to provide a hatch cover assembly that is relatively simple in construction, having but few parts that are not likely to become out of order, that provides watertight security when the hatch covers are in closed position, which permits movement of the hatchcover panels in substantially a horizontal plane from closed to open position with respect to the hatchway so that the latter is completely clear for removal and loading of cargo and without likelihood of injury to any portion of the resilient gasket effecting such watertight security and which may readily be automatically operated by even unskilled personnel to open and close the hatchway, without the need for time-consuming connection of cables to individual panels for removal thereof from the hatchway and without the need for manual stacking of the panels away from the hatchway.

According to the invention from its broader aspect, the hatchway of a ship is closed by means of a cover assembly comprising a pair of substantially rectangular panels lying in side by side relation across the hatchway in substantially a horizontal plane when in closed position. The hatchway has a peripheral upstanding coaming with a sealing rail at the upper edge thereof which is engaged by a peripheral gasket on each of the panels to effect a watertight seal. The panels are provided with suitable rollers on each side thereof adapted to ride on associated tracks. The rollers are mounted in such manner that the panels may be raised vertically prior to movement thereof to break the seal effected between the gasket and sealing rail so that the panels may thereupon be moved in a horizontal plane without likelihood of injury to the gaskets by reason of rubbing therewith.

In the preferred embodiment, one of the panels is positively driven from closed to open position and through suitable linkage connecting said driven panel with the other panel, the latter will be moved simultaneously with the movement of the driven panel but in opposite direction.

More particularly, the panels are connected by suitable cables in such manner that upon movement of the driven panel, tension will be applied through the cables to the other panel to move it in the opposite direction.

In the accompanying drawings in which are shown

one or more of various possible embodiments of the several features of the invention,

Fig. 1 is a top plan view of the hatch cover assembly with parts broken away,

Fig. 2 is a fragmentary transverse sectional view showing the coaming and a panel,

Fig. 3 is a sectional view on a greatly enlarged scale taken along line 3—3 of Fig. 1 showing a portion of the outer edge of one of the panels,

10 Fig. 4 is a sectional view taken along line 4—4 of Fig. 3,

Fig. 5 is a plan view taken along line 5—5 of Fig. 4,

Fig. 6 is a side elevational view of the hatch cover assembly in closed position,

Fig. 7 is a view similar to Fig. 6 showing the hatch cover assembly in open position, and

Fig. 8 is a detailed sectional view showing the sealing means at the inner edges of the panels.

Referring now to the drawings, in the illustrative embodiment shown, the deck 20 of the ship has a conventional hatchway 21 having a substantially rectangular coaming 22 rising from the sides and ends thereof respectively which serve to support a hatch cover assembly in the manner hereinafter to be described.

25 The side walls 23 and end walls 24 of the coaming have laterally extending plates 25, 26, each of which mounts a sealing rail 27. Positioned at one end of the hatchway at the center thereof is a housing 28 which extends outwardly from one of the ends 24 of the coaming and rises from the deck of the ship, the top wall 29 of the housing mounting sealing rails 27.

30 The hatch cover assembly illustratively comprises a pair of substantially rectangular panels A and B, each having a depending peripheral skirt 31, said panels being 35 of sufficient length so that they may extend transversely across the hatchway with the lower edges 32 of the skirt at the end edges 33 and outer side edges 34 of each panel resting on the sealing rails. The outer edge 34 of panel B has an outwardly projecting portion 36 at the center thereof adapted to be vertically aligned with the top wall 29 of housing 28 and the lower edge 37 of the depending skirt 38 of said portion 36 is also adapted to rest on the rails 27 as shown in Figs. 3 and 5.

35 In order to prevent leakage of water into the hatchway, a sealing strip or gasket 41 preferably of resilient material such as rubber, is affixed by means of a bracket 42 as illustratively shown in Fig. 2 to the periphery of each of the panels A and B at the lower edge of the skirts 31, 38 thereof and positioned inwardly thereof, the gasket seating on the associated sealing rail 27, 27' at 40 the sides and ends of the hatchway 21 to effect a seal.

45 In addition, the portions of the gasket on each of the covers A and B extending parallel to the inner edges 45, 46 thereof are designed to engage as shown in Fig. 8 when the covers are in closed position to prevent leakage 50 of water therebetween.

55 By reason of the fact that the edges 32, 37 of the skirts 31, 38 of the panels A and B rest on the sealing rails 27, 27' and the gasket 41 is positioned inwardly of said skirts the force of the waves dashing thereagainst 60 will be broken so that little pressure will be exerted against the gasket 41 to prevent injury thereto by reason of the impact of the waves.

65 As shown in Figs. 1, 6 and 7, the outer side edges 34 of each of the panels A and B adjacent each of the ends 33 thereof mounts an arm 51 which extends outwardly and downwardly therefrom. Pivotally mounted between its ends to the ends of each of the arms 51 is a link 52 which carries a flanged roller 53 at one end, said rollers riding on tracks 54 mounted on the deck 20 and 70 extending outwardly from the ends of the coaming.

Mounted on each end of the panels A and B adjacent

the inner edges 45 and 46 thereof is a link 55 pivotally mounted between its ends and carrying a flanged roller 56 at one end, resting on the outer portion of the rail 27 along the sides of the coaming which defines a track for said rollers, said rails 27 extending beyond each end of the coaming as shown at 27" in Figs. 1, 6 and 7.

Desirably, the outer end of each of the tracks 27 and 54 has an upstanding stop 58, preferably with a resilient cushion thereon against which the associated roller will abut to limit the outward movement of the panels.

Although the links 52, 55 may be pivoted in any suitable manner from the position shown in Fig. 6 to the position shown in Fig. 7 to raise the associated end of the panels A and B away from the sealing rail 27, 27' to break the seal, in the preferred embodiment shown 15 hydraulic actuators 59 are provided operatively connected to the free end of each of the links to rotate the latter.

Means are provided to effect rolling movement of the panels A and B along the tracks 27, 54, away from each other from the closed position shown in Fig. 6 to the open position shown in Fig. 7.

To this end, a pair of spaced parallel racks 61, 62 are affixed to suitable parallel beams 63 mounted on the undersurface of the panel B and extending from the outer edge of the outwardly projecting portion 36 toward the inner edge 46 thereof. One of the racks, i.e., the rack 61, is engaged by a pinion 64 affixed to a vertical shaft 65 extending through the top wall of housing 28 and driven through a reduction gear 66 by a motor M mounted on the deck of the ship in said housing. The pinion 64 engages a second pinion 67 which meshes with the other rack 62, said second pinion being an idler pinion rotatably mounted on a vertical stud shaft 68 rising from the top wall 29 of the housing 28.

Thus, when the motor M is energized in one direction, rotation of the pinion 64 in a clockwise direction from the position shown in Fig. 5 will cause the pinion 67 to rotate in a counterclockwise direction so that the racks 61 and 62 will be driven outwardly from the end of the coaming to effect movement of the panel B in a corresponding direction.

Although the panel A may be moved outwardly from the coaming by a rack and pinion drive similar to that previously described, it is preferred to utilize the construction hereinafter described.

Thus, a pair of upright transversely aligned standards 71, 72 is mounted on the deck of the ship adjacent each of the outer edges 34 of the panels A and B, each of the standards mounting a pair of independently rotatable pulleys 73 and 74. As shown in Fig. 6, a cable B' affixed at one end as at 75 to the end 33 of panel B adjacent the inner edge 46 thereof, extends the width of panel B and passes around the pulley 73 of standard 72 then extends the length of the coaming riding under the pulley 73 of standard 71 and is affixed at its free end to the arm 51 of panel A. Similarly, a cable A' is affixed at one end as at 77 to the end 33 of panel A adjacent the inner edge 45 thereof, extends the width of panel A and passes around the pulley 74 of standard 71, then extends the length of the coaming riding under the pulley 74 of standard 72 and is affixed at its free end to the arm 51 of the panel B.

Suitable means are provided to retain the panels in closed position. Such means may comprise a quick acting latch 80 having a hook 81 affixed to the panels and a pivoted member with a connecting ring 82 adapted to releasably engage the hook and affixed with respect to the coaming. As said latch may be of the type shown in patent application Serial No. 587,359, filed May 25, 1956, it will not be further described.

In the operation of the unit with the panels A and B in the closed position shown in Fig. 6, to open the panels, the latches 80 are first released by moving the connecting rings 82 away from the hooks 81. The actuators 59 on each of the panels A and B are energized to pivot

the links 52, 55 in direction to move the rollers 53, 56 on each of the panels A and B toward each other. Consequently, the panels A and B will be lifted to move the gasket 41 away from the sealing rails 27, 27' to break the seal.

Thereupon, the motor M is energized to cause the pinions 64 and 67 to rotate in a clockwise and counterclockwise direction respectively, driving the racks 61 and 62 and cover B to which they are affixed outwardly away from the hatchway, the rollers 56 and 53 riding on the tracks 27 and 54. As a result of such movement of the cover B, as one end of the cable A' is affixed to the arm 51 of panel B this will cause the end 77 thereof affixed to the inner edge of panel A to exert tension on such panel causing the latter to move outwardly in the opposite direction to the movement of panel B, the rollers 56, 53 of said panel riding on the associated tracks 27 and 54.

To move the covers to closed position from the open position shown in Fig. 7, it is merely necessary to energize the motor M in opposite direction to cause the pinions 64 and 67 to rotate in manner to drive the racks 61 and 62 and the cover B inwardly. As a result of such movement of cover B, as one end of the cable 25 B' is affixed to the inner edge 46 of panel B, tension will be applied to the cable B' which is affixed at its other end to the arm 51 of panel A and this will exert tension on panel A causing the latter to move inwardly to closed position.

With the equipment above described, a hatchway may be opened and closed by a single operator in a relatively short period of time thereby expediting the loading and unloading of a ship with resultant savings in labor and docking costs.

As many changes could be made in the above construction, and many apparently widely different embodiments of this invention could be made without departing from the scope of the claims, it is intended that all matter contained in the above description or shown in the accompanying drawings shall be interpreted as illustrative and not in a limiting sense.

Having thus described our invention, what we claim as new and desire to secure by Letters Patents of the United States is:

- 45 1. A cover assembly for a hatchway comprising a pair of panels adapted to extend over such hatchway, said panels lying in side by side relation in substantially a horizontal plane with their inner edges in juxtaposition when in closed position, a gasket mounted on the periphery of each of said panels, sealing means on each side and at the ends of the hatchway adapted to be engaged by said gaskets to provide a fluid tight seal, a pair of rollers positioned respectively on each panel at the ends thereof adjacent their inner and outer edges, track means on which said rollers ride, means mounting said rollers to effect substantially vertical movement of said panels to move the gaskets thereon away from the sealing means, a pair of rollers mounted on each side of the hatchway adjacent each of the ends thereof, a pair of cables, each affixed at one end respectively to one of the panels adjacent its inner edge, said cables when said panels are in closed position extending toward the outer edge of the associated panel, riding around one of the rollers of each of said pair of rollers at each end of the hatchway and then extending toward the other end of the hatchway, the free ends of said cables riding under the other roller at said other end of the hatchway and being secured to the other panel adjacent its outer edge, and drive means comprising a rack extending from the outer edge of one of said panels toward the inner edge thereof substantially midway between its ends, a motor mounted beyond the end of said hatchway, a pinion driven by said motor and operatively engaging said rack to effect movement of the associated panel.
- 50 2. A cover assembly for a hatchway comprising a
- 55
- 60
- 65
- 70
- 75

pair of panels adapted to extend over such hatchway, said panels lying in side by side relation in substantially a horizontal plane with their inner edges in juxtaposition when in closed position, a gasket mounted on the periphery of each of said panels, sealing means on each side and at the ends of the hatchway adapted to be engaged by said gaskets to provide a fluid tight seal, a pair of rollers positioned respectively on each panel at the ends thereof adjacent their inner and outer edges, track means on which said rollers ride, means mounting said rollers to effect substantially vertical movement of said panels to move the gaskets thereon away from the sealing means, a pair of rollers mounted on each side of the hatchway adjacent each of the ends thereof, a pair of cables, each affixed at one end respectively to one of the panels adjacent its inner edge, said cables when said panels are in closed position extending toward the outer edge of the associated panel, riding around one of the rollers of each of said pair of rollers at each end of the hatchway and then extending toward the other end of the hatchway, 20 the free ends of said cables riding under the other roller at said other end of the hatchway and being secured to the other panel adjacent its outer edge, and drive means comprising a pair of spaced parallel racks affixed to one

15

5

of said panels, said racks extending from the outer edge thereof toward the inner edge thereof, a motor mounted beyond the end of said hatchway, a pinion driven by said motor operatively engages one of said racks and a second pinion engaging the other of said racks is driven by said first pinion.

3. The combination set forth in claim 2 in which a housing is positioned outwardly of the end of said hatchway, said housing having a top wall, said motor being positioned in said housing, a shaft extending through said top wall and mounting said first pinion, said motor being operatively connected to said pinion.
